CLAIM

The ornamental design for an electrical connector, as shown and described.

DESCRIPTION

FIG. 1 is a perspective view of an electrical connector showing my design;

FIG. 2 is a right side elevation view thereof;

FIG. 3 is left side elevation view thereof;

FIG. 4 is top plan view thereof;

FIG. 5 is a bottom plan view thereof;

FIG. 6 is a rear elevation view thereof; and,

FIG. 7 is a front elevation view thereof.

The broken line portion of the figure drawings is included to show unclaimed subject matter only and forms no part of the claimed design.

1 Claim, 7 Drawing Sheets
